UNITED STATES PATENT OFFICE

JOSEPH BERLAND, OF CLEVELAND, OHIO, ASSIGNOR TO ISAAC BERLAND, OF CLEVELAND, OHIO

VENDING MACHINE

Application filed November 13, 1929. Serial No. 406,808.

This invention relates to an improved vending machine in which means are provided to discharge a newspaper or other article from within a casing when freed by 5 a coin or coins.

An object of the present invention is to provide a vending machine of the above kind embodying an improved coin-controlled mechanism which may be set so that any 10 desired one or more of several coins of different denominations may be required to operate it, according to the current price of the article or newspaper being vended.

A further object is to provide change delivering means which may be set to deliver any one of several different amounts of change when the coin-controlled mechanism is set for operation by a coin whose denomination is greater than the price of the newspaper being vended, and according to the difference between the denomination of such coin and such price of the newspaper.

With the above general objects in view, and many others that will become apparent as the nature of the invention is better understood, the same consists in the novel form, combination and arrangement of parts hereinafter more fully described, shown in the accompanying drawings, and claimed.

30 In the drawings:

Figure 1 is a front elevation, partly broken away, of a vending machine embodying the present invention.

Figure 2 is a side elevation of the machine as shown in Figure 1.

Figure 3 is an enlarged fragmentary vertical section on line 3—3 of Figure 1.

Figure 4 is a vertical transverse section taken substantially on line 4—4 of Figure 3, 40 parts being omitted.

Figure 5 is an enlarged fragmentary section taken on line 5—5 of Figure 4 to show details of the coin-controlled mechanism.

Figure 6 is an enlarged fragmentary section on line 6—6 of Figure 4.

Figure 7 is an enlarged perspective view of the reciprocating coin receiver and mover.

Figure 8 is a developed elevation showing the several coin-released detents which

control movement of the coin receiver and mover.

Figure 9 is a fragmentary vertical section through the coin tubes and associated parts of the change delivering means; and

Figure 10 is a bottom plan view of the construction shown in Figure 9.

Referring in detail to the drawings, 5 indicates an upright rectangular casing which is divided by means of a horizontal partition 6 into an upper compartment 7 and a lower compartment 8. The front of the upper compartment 7 is closed by means of a horizontally swinging door 9 which is hinged to one side of the casing as at 10, 60 and which may be locked in closed position by any suitable means. The compartment 7 is adapted to receive a stack of newspapers 11 to be vended, the same resting upon a sliding ejector plate 12 which slides on rails or wear strips 13 secured on the partition 6. The ejector plate 12 has an upstanding flange 14 at its rear edge of a height to engage the back of the lowermost newspaper only and to project the latter through the 70 front of the casing when said ejector plate is slid forwardly through a discharge slot 15 provided in the front of the casing at the bottom of the upper newspaper compartment. The discharge slot 15 is provided by 80 bending the lower edge portion of the door 9 forwardly to provide an inclined apron 16 which overhangs the slot 15 so as to protect the newspapers in the compartment from the elements in inclement weather. Attached to the front of the casing directly behind the apron 16 is a vertically adjustable slide strip 17 adapted to be set the required distance above the partition 6 to regulate the size of the slot 15 and permit discharge of only the 85 lowermost newspaper through said slot, according to the varying thicknesses of the newspapers vended at different times. The ejector plate 12 is guided in a rectilinear direction by means of a depending arm 18 rigid therewith and projecting through an elongated slot 19 provided in the partition 6. A vertically swinging lever 20 is pivoted at one end to the back of the casing 5 within the lower compartment 8, as at 21. The 90

95

Figure 10 is a bottom plan view of the construction shown in Figure 9.

Referring in detail to the drawings, 5 indicates an upright rectangular casing which is divided by means of a horizontal partition 6 into an upper compartment 7 and a lower compartment 8. The front of the upper compartment 7 is closed by means of a horizontally swinging door 9 which is hinged to one side of the casing as at 10, 60 and which may be locked in closed position by any suitable means. The compartment 7 is adapted to receive a stack of newspapers 11 to be vended, the same resting upon a sliding ejector plate 12 which slides on rails or wear strips 13 secured on the partition 6. The ejector plate 12 has an upstanding flange 14 at its rear edge of a height to engage the back of the lowermost newspaper only and to project the latter through the 70 front of the casing when said ejector plate is slid forwardly through a discharge slot 15 provided in the front of the casing at the bottom of the upper newspaper compartment. The discharge slot 15 is provided by 80 bending the lower edge portion of the door 9 forwardly to provide an inclined apron 16 which overhangs the slot 15 so as to protect the newspapers in the compartment from the elements in inclement weather. Attached to the front of the casing directly behind the apron 16 is a vertically adjustable slide strip 17 adapted to be set the required distance above the partition 6 to regulate the size of the slot 15 and permit discharge of only the 85 lowermost newspaper through said slot, according to the varying thicknesses of the newspapers vended at different times. The ejector plate 12 is guided in a rectilinear direction by means of a depending arm 18 rigid therewith and projecting through an elongated slot 19 provided in the partition 6. A vertically swinging lever 20 is pivoted at one end to the back of the casing 5 within the lower compartment 8, as at 21. The 100

lever 20 projects forwardly through a vertically elongated slot 22 provided in the upper central portion of the door 23, which closes the front of the lower compartment 8, and the intermediate portion of said lever 20 is connected by a link 24 to the lower end of the arm 18. It is thus apparent that when the lever 20 is manually depressed, the ejector plate 12 will be slid forwardly to project the lowermost newspaper 11 outwardly through the discharge slot 15 for a sufficient distance so that it may be grasped and entirely removed. The link 24 is steadied and supplemented in its action by means of a shorter link 25 pivoted to the under side of the partition 6 and extending downwardly and rearwardly where it is pivoted to the link 24 intermediate the ends of the latter. A spring 26 normally raises the lever 20 and returns the ejector plate 12 to its rearward position ready for the next newspaper ejecting operation.

Coin-released means are provided for normally locking the lever 20 substantially in its raised position, so that it may not be operated to dispense a newspaper unless a coin or coins of the required kind are deposited in the machine. These means include a vertically swinging lever 27 pivoted to the rear side of door 23 to swing in a plane parallel with the latter, and having a plate 28 rigid with its free end which is formed with a shoulder 29 disposed directly under the lever 20. The plate 28 is arranged to overlie and close the portion of slot 22 below the lever 20 when the latter is raised, thereby preventing free entrance of rain, dirt, or the like into the casing. Toggle links 30 are respectively pivoted to the intermediate portion of lever 27 and to the door 23, while the pivotally connected ends of said toggle links 30 are also connected by means of a link 31 with the stem 32 of a reciprocating coin receiver and mover 33. The coin receiver and mover 33 consists of a block slidably mounted between spaced guides 34 fixed to the door 23, and having three slots 35, 36, and 37 in one end registering with the respective ones of coin slots 35a, 36a and 37a provided in the door 23. The stem 32 of the block 33 slidably extends through a fixed guide 38 so that said block 33 is held in position against the inner face of the door 23. Pivoted to the guide 38 are a plurality of detents 39, 40, 40a, 40b, and 41, all having projecting bills 42 at their free ends. The detent 39 is carried by a thick plate 43, and its bill 42 projects into the slot 35 of block 33. The bills of the three detents 40, 40a and 40b project into the slot 36 of block 33, and the bill of detent 41 projects into the slot 31 thereof. The detents 40, 40a, 40b and 41 are separately pressed forwardly to enter their bills 42 into the respective slots 36 and 37, by means of

springs 44. Each spring 44 is attached at one end to the associated detent and bears at its other end on a bracket 45 attached to the guide 38. A transverse shoulder 46 is formed on the inner face of the block 33 near its inner end, and the detents 40, 40a, and 40b have projecting teeth 47 which are normally arranged in the path of said shoulder for engaging the latter and preventing sufficient movement of the block 33 and the lever 20 to effect ejection of a newspaper from the compartment 7. As shown in Figure 5, however, the teeth 47 are spaced from the shoulder 46 so that the block 33 may be moved a limited distance by means of the lever 20, thus allowing the block to shove the coin or coins past the bills 42 of the operative detents so as to release the latter preparatory to further depression of lever 20 and ejection of a newspaper. On the other hand, should a coin not be in position within a slot of the block 33 to release any operative detent, the tooth of that detent will engage the shoulder 46 so that further movement of the block will be prevented. This will arrest the depression of lever 20 and prevent sufficient movement of the ejector slide 12 to eject the newspaper.

It is to be noted that the slot 35a is of a size to admit a dime, but to prevent the insertion of a coin of larger size than a dime, while the slot 36a is of a size to admit a penny and to prevent the insertion of a coin larger than a penny. In a like manner, the slot 37a is of a size to admit a nickel, but to prevent the insertion of a coin larger than a nickel. Correspondingly, the bill of the detent 39 is of a form so that a coin smaller than a dime will not swing said dent 39 sufficiently to release the block 33 when it is moved by means of lever 30 and the bills of detents 40, 40a, and 40b are of a form so that coins smaller than pennies will not swing them sufficiently to move their teeth 47 out of the path of shoulder 46.

Pivoted beside the detent 41 is a latch plate 48 having a tooth 47a. A bolt 49 passes through a slot 50 and a hole 51 of the latch plate 48 and detent 41 respectively, to secure the same against relative movement. By loosening the nut on bolt 49, the latch plate may be moved relative to the detent 41 to project the tooth 47a beyond the edge of detent 41 in the path of shoulder 46 or to retract the tooth 47a inwardly of such edge and out of the path of said shoulder. By tightening the nut on bolt 49 the latch plate 48 may be fixed in either position relative to the detent 41, thus rendering the latter operative or inoperative, at will. The detents and the latch plate 48 are all notched as at 52 near their free ends to engage over a cross bar 53 which bridges the guides 34, whereby the forward movement of said detents is properly limited. It will be further noted

that the slot 36 in the block 33 is of a width to receive as many as three pennies at one time in stacked or superimposed relation. As the slot 36a is disposed near the top of slot 36, these pennies may be inserted one at a time, each to cooperate with a different one of the detents 40, 40a and 40b. It will also be seen that the first penny inserted will drop to a position so as to only operate to release the detent 40b, while the second penny inserted will drop to a position so as to only operate to release the detent 40a, the third penny inserted being directly positioned to operate and release the detent 40. The 10 detents, the plate 43, and the latch plate 49 are provided with three sets of registered openings 54, 55, and 56 adapted for selective reception of a pin 57. As shown in Figure 8, these openings in the plate 43 and the detent 39 are circular and adapted for snug reception of the pin 57. This is also true of the openings 55 and 56 of detent 40, and of openings 56 of detents 40a, 40b and 41. On the other hand, the opening 54 of 20 detent 40 and the openings 54 and 55 of detents 40a, 40b and 41 are variously elongated transversely thereof. The openings 54, 55 and 56 of latch plate 48 are all variously elongated. The forms of these openings is 25 such that when the pin 57 is inserted through the openings 56 of all of the detents, the latter will be caused to move in unison and release the block 33 when a single coin of proper denomination is placed in 30 any one of the three slots 35a, 36a or 37a. Thus, if the nickel slot is left open and the penny and dime slots are closed, the machine may only be operated after insertion of a nickel. Conversely, if the penny and nickel 35 slots are closed and the dime slot is left open, the machine may only be operated after insertion of a dime.

When the pin 57 is inserted through the openings 55 of all of the detents, the elongated form of the said openings of the detents 40a, 40b and 41 will leave the latter all free for independent release so that all of them must be released before the block 33 can be actuated sufficiently to effect the ejection of a newspaper. This will require the insertion of a nickel and two pennies when the price of the paper is seven cents, the penny slot 36a and the nickel slot 37a being both left open for that purpose. The latch 45 plate 48 is of course operatively positioned at this time. The same operation takes place when the price of the paper is eight cents, but the pin 57 is then inserted through the openings 54 of all of the detents, there- 50 by additionally leaving the detent 40 free for independent release, along with the detents 40, 40b and 41. Should the price of the newspaper be six cents, the pin 57 is inserted through the openings 56 of the de- 55 tents 39, 40, 40a and 40b, but not in the open-

ing 56 of detent 41. When this is done, the detents 40, 40a and 40b may be simultaneously released by a single penny acting on the detent 40b, and the remaining active locking detent 41 may then be released by 70 inserting a nickel to complete the release of block 33, so that ejection of a paper may be effected by depression of lever 20. By retracting the latch plate 48 so as to render it inoperative and inserting the pin 57 in the openings 56 of all detents except detent 41, the machine is set for operation upon insertion of a single penny. A like condition with the pin transposed to the openings 55 of all detents except detent 41 will set the 75 machine for operation only upon insertion of two pennies, while a mere change of the pin at this time to extend through the openings 54 of all detents except detent 41 would set the machine for operation only upon insertion of three pennies. Set screws 58 are carried by the plate 43 for engagement with the pin 57 to retain it in its various positions with the openings 54, 55, and 56 of the de- 80 tents.

On the outer face of the door 23 is arranged a plate or disk 59 having a slot 60 at one point of a size adapted to permit the passage of a dime therethrough, but to prevent the passage of a coin larger than a dime. At another point, the plate 59 has a nickel slot 61 similar to the slot 37a, while at still another point said plate has adjacent penny and nickel slots 62 and 63, respectively. Pivoted to the inner side of the door 23 is a lever 64 which is normally raised by a spring 65, and which has a square opening to receive the square stem 66 rigid with the center of the plate 59. The stem 66 passes through a vertical elongated slot 67 in the door 23, and is normally raised by the spring 65 along with the lever 64. The stem 66 is removably held in place by a pin 68 or the like, and by removing this pin, the plate 59 may be detached and turned to position the 100 slot 60, the slot 61, or the slots 62 and 63 in vertical alinement with the slots 35a, 36a and 37a. The slots in the plate 59 are so arranged that when said plate is in its normally raised position, the particular slot or 105 slots of such plate which is or are vertically alined with the coin slots of the door 23 will be out of registry with the latter. For example, the slots 62 and 63 are shown in Figure 6 as vertically alined with the coin 110 slots 35a, 36a and 37a but out of registry with the latter when the plate 59 is raised. The slots of door 23 are thus normally closed by the plate 59, and by depressing the latter by means of 115 its handle 69 the slots 62 and 63 are registered with the corresponding slots 36a and 37a of said door to permit the insertion of pennies and a nickel for effecting operation of the machine, the slot 35a being, however, 120 125 130

maintained closed. An arm 70 is rigid with the lever 64 and projects rearwardly therefrom above the detents. This arm terminates in a depending free end 71 normally 5 elevated out of the path of detent 39 and plate 43 but movable into the path of the same when the plate 59 is depressed to open the coin slot or slots of door 23, thus preventing rearward release movement of the 10 detents while the latter slot or slots are open. This prevents tampering with or release of the detents by means other than coins, such as a knife, wire or the like.

It is sometimes undesirable to set the coin-controlled mechanism so that it may only be operated when the customer possesses one or more pennies in change. For instance, it may be desirable to permit operation of the machine when a nickel is inserted and the 15 price of the newspaper is less than five cents. For this purpose, means are provided for delivering change to the customer corresponding to the difference between the denomination of the single coin inserted and the 20 price of the article or newspaper. These means embody a group of four vertical penny-storage tubes 72 mounted as at 73 in the lower compartment 8 behind the coin-controlled mechanism. A plate 74 is fixed 25 beneath and in slightly spaced relation to the lower ends of the tubes 72, said plate having four openings corresponding in size and general location with the tubes 72, but offset rearwardly to a slight extent relative 30 to the latter. A correspondingly apertured slide 75 is mounted between the lower ends of the tubes 72 and the plate 74, such slide being normally yieldingly retracted toward the front of the casing by means of a spring 35 76 so that its apertures are alined with the tubes 72 and are positioned to receive the lowermost ones of the pennies stacked in the associated tubes 72. It is thus apparent that the stacks of pennies in the tubes will be 40 normally supported by the fixed plate 74, and that the lower penny of each stack will be positioned in an aperture of the slide 75. Thus, when the slide 75 is moved rearwardly 45 four pennies will be carried rearwardly thereby to positions in registry with the openings of plate 74, and if the latter openings are all left open, all four pennies will be discharged therethrough into a coin-return chute 77 disposed beneath the tubes. 50 The chute 77 leads to an opening 78 in the door 23 so that the customer may readily remove the change so delivered. Thus, if the machine is operated by the insertion of a nickel, four pennies change will be 55 delivered to the customer when the price of the newspaper is one cent. By closing one or more of the openings of plate 74, the 60 number of pennies change delivered may be varied according to any change in the price of the paper up to four cents. For this pur-

pose, a plate 79 is provided for attachment to the under side of plate 74, by suitable means 80, in any desired one of four different positions to respectively close either one, two, three or all of the openings of said plate 74. Obviously, the plate 79 may be set so that one penny change will be delivered when the price of the paper is four cents and the machine is set for operation by inserting a nickel, or when the price of the paper is nine cents and the machine is set for operation by inserting a dime. It will be noted that the block 33 and guides 34 are slightly inclined so that the coins will be delivered from the block 33 by gravity, after actuation of said block and upon its return to normal position after each vending operation.

In operating the machine, we will assume that the machine is set as shown in the drawings with the pin 57 engaged in the openings 56 of detents 39, 40, 40a and 40b, but not in the opening 56 of detent 41. The latch plate 48 is also in projected or in an operative position, and the slots 62 and 63 are disposed to be registered with the slots 36a and 37a when the plate 59 is depressed. These conditions maintain when the price of the newspaper is six cents, and when a nickel is inserted to occupy a position in the slot 37 of block 33 and a penny is inserted to occupy a position in the slot 36 thereof, the lever 20 is depressed so as to cause such penny and nickel to be moved by the block under the bills 42 of the detents 40b and 41. This swings the detent 40b so that its tooth 47 is moved out of the path of shoulder 46, and as the detents 40 and 40a are caused to move with the detent 40b by means of the pin 57, the teeth 47 of said detents 40 and 40a are also moved out of the path of shoulder 46. At the same time, such operation causes separate movement of the detent 41 so that the tooth 47a of its latch plate 48 is also moved out of the path of shoulder 46. The block 33 is thus completely released and permitted to move still further upon continued depression of lever 20, thereby allowing actuation of the ejector plate 12 so that the lowermost paper in the compartment 7 will be projected through the slot 15 for such a distance that it may be readily grasped and entirely removed. The coins inserted then slide out of the slots 36 and 37 over the lower end of the bottom guide 34, from whence they fall onto the bottom of the casing 5 at one side of the chute 77. The lever 20 is then released so that the spring 26 may reset or return the various associated movable parts to normal position and to permit the springs 44 to return the detents to normal position.

It will be understood that the front end of the slide 75 is disposed in the path of detent 41 so that it will be automatically

operated by said detent to deliver change when said detent 41 is released and one or more of the openings of plate 74 is or are left open. The openings of plate 74 are all closed, or no coins are placed in the tubes 72, however, when the machine is set for any operation wherein the delivery of no change is desired, such as when the price of the paper is six cents and the machine is set as just described.

The door 23 is preferably hinged at the bottom as at 81, to swing downwardly to open position, and suitable means 82 are provided to lock the said door in closed position.

From the above description, it is believed that the construction and operation of the invention will be readily understood by those skilled in the art.

Minor changes are contemplated within the spirit and scope of the invention as claimed.

What I claim as new is:

1. In a vending machine, a coin-controlled mechanism including a reciprocating coin receiver and mover, a plurality of coin-released pivoted detents, certain of said detents being normally spring-pressed into position to arrest movement of said coin receiver and mover, and means to selectively connect certain or all of said detents in any various relations for independent movement or movement in unison, whereby the mechanism may be set for causing release of said detents from the path of the coin receiver and mover upon insertion of any desired one of several coins of different denominations.
2. In a vending machine, a reciprocating block having slots for reception of coins of different denominations, one of said slots being adapted for reception of a plurality of coins of one denomination, a plurality of independent coin-released detents associated with the last named slot and normally spring-pressed into position to arrest movement of said reciprocating block, further coin-released detents respectively associated with each of the remaining slots, and means to render one of the last named detents operative or inoperative to arrest movement of said reciprocating block, at will.
3. In a vending machine, a reciprocating block having slots for reception of coins of different denominations, one of said slots being adapted for reception of a plurality of coins of one denomination, a plurality of independent coin-released detents associated with the last named slot and normally spring-pressed into position to arrest movement of said reciprocating block, further coin-released detents respectively associated with each of the remaining slots, and means to render one of the last named detents operative or inoperative to arrest movement
- of said reciprocating block, at will and means to selectively inter-connect certain or all of said detents in any desired one of several ways to permit release of the block upon insertion of one coin of either denomination or upon insertion of several coins of different denominations.
4. In a vending machine, a reciprocating block having slots for reception of coins of different denominations, one of said slots being adapted for reception of a plurality of coins of one denomination, a plurality of independent coin-released detents associated with the last named slot and normally spring-pressed into position to arrest movement of said reciprocating block, further coin-released detents respectively associated with each of the remaining slots, and means to render one of the last named detents operative or inoperative to arrest movement of said reciprocating block, at will and means to selectively inter-connect certain or all of said detents in any desired one of several ways to permit release of the block upon insertion of one coin of either denomination or upon insertion of several coins of different denominations, a casing having coin slots registered with the slots of said block, means normally closing said coin slots of the casing and movable and adjustable to uncover any desired one or several of the same, and means operable by said coin slot closing means for preventing release of the detents while a slot or slots of the casing are uncovered.
5. In a vending machine, a reciprocating block having slots for reception of coins of different denominations, one of said slots being adapted for reception of a plurality of coins of one denomination, a plurality of independent coin-released detents associated with the last named slot and normally spring-pressed into position to arrest movement of said reciprocating block, further coin-released detents respectively associated with each of the remaining slots, and means to render one of the last named detents operative or inoperative to arrest movement of said reciprocating block, at will and means to selectively inter-connect certain or all of said detents in any desired one of several ways to permit release of the block upon insertion of one coin of either denomination or upon insertion of several coins of different denominations, and means operable by one of said detents for delivering change.
6. In a vending machine, a reciprocating block having slots for reception of coins of different denominations, one of said slots being adapted for reception of a plurality of coins of one denomination, a plurality of independent coin-released detents associated with the last named slot and normally spring-pressed into position to arrest movement of said reciprocating block, further

coin-released detents respectively associated with each of the remaining slots, and means to render one of the last named detents operated or inoperative to arrest movement of said reciprocating block, at will and means to selectively inter-connect certain or all of said detents in any desired one of several ways to permit release of the block upon insertion of one coin of either denomination or upon insertion of several coins of different denominations, and means to vary the amount of change delivered by said last named means when operated by said detent.

7. In a vending machine, a reciprocating block having slots for reception of coins of different denominations, one of said slots being adapted for reception of a plurality of coins of one denomination, a plurality of independent coin-released detents associated with the last named slot and normally spring-pressed into position to arrest movement of said reciprocating block, further coin-released detents respectively associated with each of the remaining slots, and means to render one of the last named detents operative or inoperative to arrest movement of said reciprocating block, at will, said detents having a plurality of sets of registered openings, certain of said registered openings being circular and the rest being variously elongated transversely of the detents, and a pin selectively positionable in any desired set of openings of certain or all of said detents to vary the denomination or number of coins required to be inserted to effect release of said block.

8. In a vending machine, a reciprocating block having slots for reception of coins of different denominations, one of said slots being adapted for reception of a plurality of coins of one denomination, a plurality of independent coin-released detents associated with the last named slot and normally spring-pressed into position to arrest movement of said reciprocating block, further coin-released detents respectively associated with each of the remaining slots, and means to render one of the last named detents operative or inoperative to arrest movement of said reciprocating block, at will, an operating lever operatively connected to said block, an article ejector operatively connected to said lever, and a spring to yieldingly raise said lever and reset said block and said article ejector.

9. In a vending machine, a movable coin receiver, coin-released locking detents therefor, means to selectively inter-connect said detents in any one of several ways to control the denomination or number of coins required to unlock said coin receiver, an article ejector, and an operating lever operatively connected to said coin-receiver and said article ejector.

10. In a vending machine, a movable coin

receiver, coin-released locking detents therefor, means to selectively inter-connect said detents in any one of several ways to control the denomination or number of coins required to unlock said coin receiver, an article ejector, and an operating lever operatively connected to said coin-receiver and said article ejector, and means to render one of said detents operative or inoperative, at will.

11. In a vending machine, a movable coin receiver, coin-released locking detents therefor, means to selectively inter-connect said detents in any one of several ways to control the denomination or number of coins required to unlock said coin receiver, an article ejector, and an operating lever operatively connected to said coin-receiver and said article ejector, and means to render one of said detents operative or inoperative, at will, and change delivering means operatively connected to the last named detent.

12. In a vending machine, a movable coin receiver, coin-released locking detents therefor, means to selectively inter-connect said detents in any one of several ways to control the denomination or number of coins required to unlock said coin receiver, an article ejector, and an operating lever operatively connected to said coin-receiver and said article ejector, and means to render one of said detents operative or inoperative, at will, and change delivering means operatively connected to the last named detent, and an adjustable plate for controlling the amount of change delivered by said change delivering means.

In testimony whereof I affix my signature.
JOSEPH BERLAND.
